CLAIM

The ornamental design for socks, as shown and described.

DESCRIPTION

FIG. 1 is a bottom plan view of a sock showing my new design, solid black being used in the drawings to indicate color contrast;

FIG. 2 is a side elevational view thereof, the opposite side is a mirror image, the sock is of conventional thickness; FIG. 3 is a side elevational view of a second embodiment of a sock showing my new design, the sock is of conventional thickness;

FIG. 4 is a bottom plan view thereof;

FIG. 5 is a bottom plan view of a third embodiment of a sock showing my new design, the side being similar to FIG. 3; FIG. 6 is a bottom plan view of a fourth embodiment of a sock showing my new design; and,

FIG. 7 is a side elevational view, the opposite side is a mirror image.
